Inventor:

E. Warren Smeeton

UNITED STATES PATENT OFFICE.

EDWARD WARREN SMEETON, OF LONG ISLAND CITY, NEW YORK.

LAMP.

1,389,077.

Specification of Letters Patent. Patented Aug. 30, 1921.

Application filed January 29, 1919. Serial No. 273,827.

To all whom it may concern:

Be it known that I, EDWARD WARREN SMEETON, a subject of the King of Great Britain, residing at Long Island City, in the county of Queens, State of New York, have invented certain new and useful Improvements in Lamps, of which the following is a full, clear, concise, and exact description.

This invention relates to a lamp.

10 It relates more particularly to an oil burning lamp.

Such a lamp is particularly useful for heating incubators, although not limited to such use.

15 Heretofore when oil burning lamps have been employed for heating incubators it has been necessary to periodically remove such lamps therefrom for refilling the same and trimming the wick.

20 In such lamps the rate of carbonization at the flame end of the wick has varied between wide limits.

Due to these and other causes it has not been possible to maintain uniform temperatures in incubators heated by oil burning lamps; whereas it is highly important that a uniform temperature be maintained if the incubator is to be efficiently operated.

An object of the invention is to provide 30 improved means for removing the carbon from the flame end of the lamp wick while the lamp is burning without extinguishing the flame and without removing the lamp from the incubator.

35 Other objects and advantages will appear from the following description and claims.

In attaining the objects of the invention the lamp is provided with means positioned within and operable from without the lamp 40 burner inclosure for removing the carbon from the wick while the lamp is burning and without extinguishing the flame. The lamp also has associated with the oil well thereof an oil reservoir for maintaining the oil in the oil well at a constant level and for controlling the rate of carbonization of the lamp wick.

An embodiment of the invention is illustrated in the accompanying drawings 50 wherein:

Figure 1 is a side elevation of the lamp equipped with the wick trimmer and the associated oil receiver;

Fig. 2 shows the trimmer mounted within 55 the cone of the burner; and

Fig. 3 shows the trimmer in operative relation to the wick.

As shown in the drawings, the base 5 of the burner of the lamp is secured to the upper end of an oil well 6, preferably and as usual, by means of external threads provided on the lower end of the base, engaging internal threads provided in the rim of an opening in the upper end of the oil well. An oil reservoir 7 is connected with the oil well 6 by means of a pipe 8. The supply of oil in the reservoir 7 may be maintained by means of an upturned bottle 9. The mouth of the bottle 9 should be at the level at which it is desired to maintain the oil in the oil well 6. The bottle may be large enough to hold sufficient oil, whereby the oil in the receptacle is maintained at a constant level for a period ranging from two to four days, without replenishing the supply in the reservoir. A valve arrangement is preferably employed in connection with each bottle for maintaining the opening thereof closed, until the bottle is in resting position in the reservoir, as shown in Fig. 1. This arrangement for normally maintaining the mouth of the bottle closed except when in the position shown in Fig. 1 may comprise a cap 27 secured to the mouth of the bottle. The cap 27 is provided with an opening 28 which may be closed by means of a cone-shaped plug 29 secured to a rod 30 passing through the center thereof. A coiled spring 31, one end of which engages the base of the plug 29 and the other the base portion of a U-shaped bracket 32 secured to the cap 27 of the valve tends normally to force the plug 29 into the opening 28. When the upturned bottle is in the reservoir 7, the end of the rod 30 engages the bottom of the reservoir 95 and the weight of the bottle and its contents causes the compression of the spring 31, thereby causing plug 29 to move out of the opening 28, so that oil will then flow out of the bottle into the reservoir. 100

The burner is of well-known construction, comprising the base 5, a wick tube 10, through which extends a wick 11, which may be raised or lowered by means of a wick adjuster 12. Above and on the base 5 is mounted a platform 14 having an upturned edge 15 within which fits the lower end of a metallic chimney 15. The chimney 15 is provided with a window 26 of mica, through which the flame issuing from the wick 11 110

may be seen. The upper end of the chimney 25 fits into the lower end of the usual heater 16 attached to the incubator by means of a short pipe 33 and through which the air heated by the lamp passes into the incubator. The heater 16 is very heavily insulated by means of asbestos to prevent sudden changes of outside temperature from affecting the temperature of the incubator. 10 Upon the platform 14 is mounted a burner cone 17 having a slot 18 through which the flame from the wick 11 issues. The lamp including the reservoir may be supported by a suitable bracket 34 secured to the incubator 15 to 35.

The wick trimmer comprises a flat sharp-edged L-shaped member 20, the short arm of which is secured to a rod 21 journaled at two points in the cone 17. The rod 21 is so mounted that it is parallel to the flat side of the wick tube 10, so that when the L-shaped member 20 is swung into the position shown in Fig. 3 by turning up the ends of the supporting rod 21, the rod may be moved horizontally to shift the tapered free arm of the member 20 back and forward across the top of the wick 11 to scrape off the carbon formed thereon. The width of the free arm or cutting portion of the member 20 is such that it is in contact with only a small portion of the width of the wick at one time, whereby the carbon may be effectively removed without interfering with the flame. In order that the wick trimmer may be operated from without the chimney 25, and without removing the lamp from the incubator or from operative relation to the heater 16, the rod 21 is made long enough to extend through very small slots provided 40 in the opposite sides of the chimney 25. The ends of the rod are bent at substantially right angles to the rod to provide ready means for turning the rod, or for moving it horizontally. Thus the carbon may be removed from the burning lamp wick without extinguishing the flame and without removing the lamp from the incubator heated thereby.

While certain advantages are secured by 50 employing either the reservoir for maintaining the oil in the oil well at a constant level, or the wick trimmer, still greater advantages are secured when these two features are combined in the same lamp. It 55 will be evident that the shorter the distance from the oil in the oil well to the flame end of the wick, the more thoroughly will the

wick be saturated, therefore the least carbonization will take place at the flame end of the wick, provided however that this distance be maintained uniform. The many advantages in the use of the wick trimmer embodying the features of the present invention will be apparent to any one familiar with the operation of incubators and the necessity for maintaining therein a uniform temperature.

What I claim is:

1. In an oil burning lamp, the combination of a burner, having a wick therein, an inclosure for the upper portion of the burner, a flat tapered wick trimmer having both edges arranged to trim the wick, and an operating rod therefor extending through and supported by the inclosure. 75

2. An oil burning lamp comprising a burner having a wick therein, a cone inclosing the burner and having a slot through which the flame from the wick issues, a wick trimmer within the cone arranged to trim the wick while it is burning without extinguishing the flame, the wick trimmer having a flat tapered arm for engaging the wick and an angular extension, and an operating rod to which the angular extension 80 is fastened.

3. An oil burning lamp comprising a burner having a wick therein, a cone inclosing the burner and having a slot through which the flame from the wick issues, a wick trimmer within the cone arranged to trim the wick while it is burning without extinguishing the flame, the wick trimmer having a flat tapered arm for engaging the wick and an angular extension, and an operating rod for the trimmer extending through and supported by the cone, the operating rod having a short loop formed 90 therein to which the trimmer extension is rigidly fastened. 95

4. An oil burning lamp comprising a burner having a wick therein, a cone inclosing the burner and having a slot through which the flame from the wick issues, an actuating rod having a portion thereof within the cone formed into a loop, and an L-shaped wick trimmer having one arm thereof rigidly fastened to the loop and its free arm forming a flat tapered double-edged cutter. 105

In witness whereof I hereunto subscribe my name this 18th day of January, A. D. 110 1919.

EDWARD WARREN SMEETON.
